(No Model.)

W. T. RODGERS.

CAR COUPLING.

No. 361,375.

Patented Apr. 19, 1887.

UNITED STATES PATENT OFFICE.

WILLIAM THOMAS RODGERS, OF MOUNT UNION, PENNSYLVANIA.

CAR-COUPING.

SPECIFICATION forming part of Letters Patent No. 361,375, dated April 19, 1887.

Application filed February 8, 1887. Serial No. 226,964. (No model.)

To all whom it may concern:

Be it known that I, WILLIAM THOMAS RODGERS, a citizen of the United States, residing at Mount Union, in the county of Hunt and State of Pennsylvania, have invented new and useful Improvements in Car-Couplings, of which the following is a specification.

My invention relates to improvements in car-couplings; and it consists in the construction, combination, and arrangement of the several parts, hereinafter first fully described, and then pointed out in the claims.

In the annexed drawings, which fully illustrate my invention, Figure 1 is a side elevation of two car-couplings constructed in accordance with my invention in position to be coupled together. Fig. 2 is a vertical transverse section taken on the line xx of Fig. 1. Fig. 3 is a vertical longitudinal section, and Fig. 4 is a perspective view, of the link-guide and coupling-pin and the securing-clamp removed from the draw-head.

Referring to the drawings by letter, A designates the draw-head, of any preferred construction, having the annular flange a around its outer end. The draw-head is secured to the under side of the car, as shown, in the ordinary manner.

B is a sliding block working in the draw-head, which, in operation, presses against the end of the link and holds it in engagement with the coupling-pin. This sliding block is provided on its outer end with the usual recesses for the reception of the pin and end of the link, and has the usual rearward extension, B', around which a spring, C, is coiled between the block B and a stop, c, formed on the inside of the draw-head. The sliding block is also provided with a notch, b, on its upper side, and the said notch is engaged by a guide, b', on the upper inner face of the draw-head. The sliding block is thus caused to move steadily and firmly in a straight line.

D is a plate secured to the under side of the draw-head at or near its forward end. This plate D may be bolted to the draw-head below the lower plate of the clamp, hereinafter referred to; but I prefer to form it integral with the said plate and projecting from the rear edge of the same. In whatever manner, however, it may be formed and secured to the

draw-bar, a space, d, must be provided between its upper face and the under side of the draw-bar to admit the band, which secures the draw-head to the under side of the car.

55

The link-guide E is pivotally secured to the edges of the plate D by means of pivot-pins inserted through the ends of the arms e of the link-guide into the edges of the said plate. These arms e extend from the opposite sides 60 of the link-guide up to the opposite sides of the plate D, and are connected to the pin-carrier by the links F, which are pivotally secured at their opposite ends to the ends of the pin-carrier G and the arms e. The bolt 55 f, which secures the lower ends of the links F to the arms e also holds the said arms in their proper positions relative to each other, and a notch, f', is formed on the under side of the plate D, near its front end, to receive the said 70 bolt when the link-guide is elevated. The link-guide E is secured upon the arms e, at their outer ends, at an angle to said arms, so that when elevated it will incline forwardly and downwardly from the mouth of the draw-head in position to direct the approaching link up to and into the same. This link-guide may be formed of any suitable material, and just behind it I form notches e' on the upper sides of the arms e, to receive the flange a 80 when the guide is elevated.

The pin-carrier G is, as before stated, pivotally connected to the link-guide by the links F, and, as will be readily seen, is operated simultaneously by and with the link-guide. 85 The coupling-pin H is inserted through an opening provided for the same at the center of the carrier, and in operation passes through openings in the top and bottom of the draw-head, all of said openings being in vertical 90 alignment. The pin is provided with an enlargement, h, at its upper end, which prevents its falling through the carrier, thereby choking the draw-head and impairing the efficiency of the device,

To prevent the pin being forced up and out of the carrier, I provide a latch, g, which is pivotally secured upon the upper side of the carrier and swings around over the upper end of the pin. The carrier is guided in its movements by two vertical guide-rods, I, which project upward from the draw-head and pass

95

100

through openings in the carrier, near the opposite ends thereof. These guide-rods I pass through the clamping-plates J K, which are arranged above and below the draw-head just 5 back of the annular flange *a*, and the lower ends of the guide-rods are screw-threaded and carry retaining-nuts *i*, which are turned up against the lower clamping-plate, *k*, to secure the said plates to the draw-head.

- 10 In order that the rods I may not be drawn through the upper clamping-plate, and the said plates consequently fail to bind against the draw-head, I provide the said rods I with enlargements or lugs *j*, which fit in recesses in 15 the upper side of the said clamping-plate, and consequently prevent the rods being drawn therethrough. Between the coupling-plates the rods I are provided with enlarged portions or sleeves L, which assist in guiding the sliding block B in its movements in the draw-head.

20 To the inner side of each of the connecting-links I secure the springs M, having enlargements *m* at their upper free ends, as shown. The enlargements *m* of these springs engage the 25 upper clamping-plate, J, and prevent the accidental raising or lowering of the coupling-pin and link-guide.

From the foregoing description it will be seen that the coupling-pin and link-guide are 30 operated simultaneously, and that the clamping-plates J K are all that I employ to secure the same to the draw-head. It will also be seen that should any part become injured it can be easily and quickly replaced by a new 35 piece without necessitating an entirely new coupling. It will also be seen that my device can be used as an ordinary coupling by simply turning the latch *g* around to one side, when the pin can be set by hand to operate in the 40 usual manner.

When coupling cars by the use of my device, the link is placed in one draw-head and the coupling-pin made to engage it by hand. When the coupling-pin is brought down to engage 45 the link, the same action will lower the link-guide and cause it to swing down below the draw-head, as will be readily understood. The car is now made to approach the car which it is desired to couple to the train, and which 50 has its coupling-pin and link-guide in their elevated positions, as shown. As the car carrying the link approaches, the link will impinge upon the guide and will be directed up into the draw-head. As the car continues to 55 approach, the flange *a* of the approaching draw-head will impinge upon the link-guide of the stationary car and will depress the same. When the guide falls, it will draw the coupling-pin down into the draw-head and into engagement with the link, and the operation of coupling 60 will be completed.

To uncouple it is only necessary to raise the link-guide and coupling-pin, when the link can be readily withdrawn. It will be seen from this that the same act which uncouples 65 the car also sets the coupling for action to couple the car at a future time.

When so desired, a chain or rope may be attached to the pin-carrier and carried to the top or side of the car, so that the device may 70 be operated without the necessity of the attendant going between the cars.

Having thus described my invention, what I claim, and desire to secure by Letters Patent, is—

75

1. In a car-coupling, the combination, with the draw-head, of the plate D below the same, the link-guide having the rearwardly-extending arms pivoted at their ends to the opposite edges of the said plate, the pin-carrier 80 above the draw-head, and links pivotally secured at their opposite ends to the pin-carrier and the arms of the link-guide, substantially as set forth.

2. The combination, with the draw-head, of 85 the clamping-plates above and below the same, guide-rods extending therefrom, the pin-carrier working on said guide-rods, and the link-guide pivotally supported below the draw-head and connected to the pin-carrier, substantially as set forth.

3. The combination, with the draw-head, of 90 the clamping-plates above and below the same, the guide-rods held by the same and projecting upward therefrom, the pin-carrier mounted 95 on said guide-rods, the link-guide pivotally supported below the draw-head, and connecting-links pivotally secured to the link-guide and the pin-carrier, said links carrying springs which engage the upper clamping-plate, substantially as specified.

4. The combination of the pin-carrier, the pin inserted therethrough, having an enlarged head, and the latch pivoted upon the pin-carrier and swinging over the head of the pin, substantially as set forth.

5. The combination, with the draw-head having an annular flange around its outer end, of the arms *e*, carrying the link-guide and having notches in their upper sides for the reception of the annular flange of the draw-head, said arms being pivotally secured beneath the draw-head, substantially as specified.

In testimony that I claim the foregoing as my own I have hereto affixed my signature in 115 presence of two witnesses.

WILLIAM THOMAS RODGERS.
